Attorney.

UNITED STATES PATENT OFFICE.

JAMES H. FLETCHER, OF BRIDPORT, VERMONT.

ADVERTISING-STAND.

No. 852,710.

Specification of Letters Patent.

Patented May 7, 1907.

Application filed March 9, 1905. Serial No. 249,331.

To all whom it may concern:

Be it known that I, JAMES H. FLETCHER, a citizen of the United States, residing at Bridport, in the county of Addison and State of Vermont, have invented certain new and useful Improvements in Advertising-Stands; and I do hereby declare the following to be a full, clear, and exact description of the invention, such as will enable others skilled in the art to which it appertains to make and use the same.

My invention relates to devices for advertising in a neat manner all kinds of mercantile articles, such as dry goods, canned goods, or other special merchandise.

The object of my invention is to produce a standard upon which the advertising cards can be displayed and readily placed between the piles of goods without disturbing them. As is well-known, it has been the usual custom to place the articles on a counter, table, or equivalent, in stores, and advertising them by sign holders, having a heavy board base, supporting a standard with cards, and often nailed down, to keep them in a vertical position.

Another object is, to produce a sign holder provided with a thin, metal base, supporting the standard for the advertising cards. The base is slipped between the goods on a pile, whether dry-goods, canned goods in glass jars, notions, or any other kinds of merchandise. Furthermore, to prevent the pile of goods from tilting, as is the case with standards having a thick base; also, so that the sign can be placed on the rear of the pile or on the front; and finally that it can be produced at a reasonable cost.

With these objects in view, my invention consists in the peculiar construction of certain details, and the novel arrangement of parts, as will be more fully described herein-after, and specifically pointed out in the claims, reference being had to the accompanying drawing and the letters thereon.

Like letters indicate similar parts in the different figures of the drawing, in which:

Figure 1 represents a perspective view of my improved sign holder and base. Fig. 2 is a side elevation of the same.

In the drawing, A represents a light standard, upon which the card is displayed. It is

made of wood or other suitable material and made in two parts C and D. It is held together by a collar E, and can be adjusted by a set screw e to different heights. At the lower end of the part C is arranged a slot d, into which is inserted the vertical part B' of the base B, which is horizontal, and is held in place by the pins d', d''. The corners of said base are rounded, to facilitate the introduction of the horizontal part between the bolts of dry goods, canned goods, etc., to be advertised. A collar E is placed around the two parts of the standard, and has a set screw e to adjust the parts, as desired. The upper part C is provided with two thin metal strips g, g, curved slightly toward their adjacent ends, and can be adjusted by the set screws h, h, to suit different widths of cards to be inserted between them. The card F is inserted in a slit in the upper end of the standard C.

The standard is made very light, as it has nothing very heavy to support, and also to obviate the necessity of a heavy or thick base. A thick base, if inserted, would cause the pile to tilt and perhaps cause it to fall, while my thin metal base could be readily inserted or slipped between the goods at any place, and would not take up any appreciable space or thickness. It is made of tin, sheet iron, or its equivalent. If it is desired to place the sign on the rear of the pile, the base is simply turned in on that side and the sign will then be on the rear side. If, however, the sign is to show in front of the pile, it is merely reversed. It is also well adapted for the display of notions of all kinds, small wares, several kinds of pieces of dress goods, cards of buttons, sample cans of tea, coffee, rice, spices, or any kinds of marketable articles or ware.

The many advantages possessed by my improved card displaying standard and base will be readily appreciated by merchants and others requiring such devices, and will require no further elucidations here.

Having thus described my invention, what I claim and desire to secure by Letters Patent, is:

1. The combination of a standard made in two parts, the metal base B, having a vertical part B', the lower part D having a slot d in its lower end, into which the part B' of the

metal base B is inserted, and the collar E, having the set screw e for adjusting said parts, with the metal strips g, g, provided with the set screws h, h, for adjusting said strips, arranged as specified.

2. The standard made in two parts C and D, the metal base B, having the vertical part B', in combination with the collar E, its set screw e, and the metal strips g, g, and set

screws h, h, for adjusting said strips, all as described.

In testimony whereof I hereby affix my signature, in presence of two witnesses.

JAMES H. FLETCHER.
